UNITED STATES PATENT OFFICE.

WILHELM WEBER, OF WIESBADEN, GERMANY, ASSIGNOR TO THE FIRM GEWERKSCHAFT HAUSBACH II, OF WIESBADEN, GERMANY.

APPARATUS FOR FLUSHING CONDUITS.

1,426,135.

Specification of Letters Patent. Patented Aug. 15, 1922.

Application filed January 22, 1921. Serial No. 439,273.

To all whom it may concern:

Be it known that I, WILHELM WEBER, a citizen of the German Republic, residing at Wiesbaden, Germany, have invented certain new and useful Improvements in an Apparatus for Flushing Conduits (for which I have obtained in Germany Patent No. 309795 of the 28th of March 1918), of which the following is a specification.

10 This invention relates to an apparatus designed to be mounted at a convenient point in the flushing conduit for refuse from mining. The invention is based upon the idea to use air under pressure or water 15 under pressure for assisting the flow in the flushing conduit if said conduit has to be conducted for long distances either in horizontal direction or in an upwardly inclined direction.

20 In order that the invention may be clearly understood, I shall proceed to describe the same with reference to the example of construction shown in the accompanying drawings, wherein:

25 Fig. 1 is a side elevation of the auxiliary device, the main tube being shown in section.

Fig. 2 is a plan view of the Fig. 1, and Fig. 3 is a cross section of Fig. 1.

30 Fig. 4 shows a modified form of construction in side elevation.

Fig. 5 is a cross section of Fig. 4.

The auxiliary apparatus shown in Figs. 1, 2 and 3 is tube-shaped and composed of 35 an upper part 1 and of a lower part 2 which are riveted or welded together to form a tube. The upper part 1 has its edges bent inwardly in spiral-shape so that two pipes 3, 4 of small cross section are formed. The 40 edges of the upper part 1 of the tube are arranged so that at either side a slot 5 is formed. The tube is thus divided into four chambers of which the upper one 6 is designed to receive a pipe 7 for the supply of 45 pressure air or of water under pressure. Spraying pipes 8 branch off laterally from the pipe 7 reaching into the slots 5 of the tubes 3 and 4. Tubular connecting pieces 50 9 and 10 whose cross sections correspond with the cross sections of the tubes 3 and 4 are arranged at the two ends of the apparatus.

The operation of the apparatus is as follows:

55 Air under pressure or water under pres-

sure is supplied to the apparatus before the flushing is started. When the flushing has been started properly air under a pressure of 2-7 atm. is admitted. The pressure passes from the chamber 6 through the slots 5 and rotates the flushing material. As the same pressure or even a higher pressure comes from the spraying pipes 8 and as these spraying pipes are situated in the direction of movement of the flushed material this material which is strongly rotating is simultaneously pressed forward. The pressure is not only utilized for moving the material forward and for rotating the same but also for ensuring an intimate mixing of 70 said material.

It is particularly important that material conveyed by flushing which enters the apparatus through the tubular connecting piece 9 is divided into two flows of reduced cross 75 section when getting into the tubes 3 and 4 whereby the speed of the material is increased.

If however instead of the tubular chambers 3 and 4 of reduced cross section one large 80 passage is required, this being preferable with wide spreading material such as slate or the like, the form of construction shown in Figs. 4 and 5 is preferably used.

The apparatus shown in Figs. 4 and 5 consists of a tubular body 11 of essentially cylindrical shape, designed to be inserted in the flushing conduit. Upon the tubular body 11 a separate chamber 12 is arranged which extends almost over the entire length 90 of tubular body 11. The chamber is closed by a removable lid 13 which has a tubular socket 14 to which the supply for the pressure air is to be connected. Channels 15 which are preferably arranged directly in 95 the wall of the tubular body 11 connect the chamber 12 with said tubular body. These channels stand at an angle with regard to the direction of movement of the material conveyed through the tubular body 11 so 100 that they exert a rotating and pushing effect upon the material in the direction of flow. This apparatus permits therefore to assist the flushing flow to overcome horizontal or inclined lengths.

105 As the apparatus is closed tightly it is impossible that the pressure air escapes without being utilized.

I claim:

1. Apparatus to be inserted in flushing

conduits for refuse from mining and designed to increase the speed of flow and to help to get over long horizontal or inclined parts of the tubular closed conduit comprising in combination with the flushing conduit a tubular body to be inserted in said flushing conduit composed of two parts connected by riveting or welding, the edges of the upper part being curved inwardly to form tubular conduits for the material to be conveyed by flushing, said tubular conduits being of small cross section and said edges being not in contact with the inner wall of said upper part so that longitudinal slots are formed, a source of fluid under pressure, a pipe in the chamber above said two tubular conduits connected with said source of air or water under pressure, and spraying pipes radially projecting from said pipe and terminating tangentially and obliquely into said slots of said tubular conduits.

2. An apparatus to be inserted in flushing conduits for refuse from mining and de-

signed to increase the speed of flow and to help to get over long horizontal or inclined parts of the tubular closed conduit comprising in combination with the flushing conduit, with a tubular body inserted in said flushing conduit and with a source of fluid under pressure, a chamber mounted upon said tubular body designed to receive the fluid under pressure and radial channels arranged in the inner surface of the wall of the tubular body whose orifices stand tangentially and obliquely to the flow of material in said tubular body and designed to connect said chamber with the source of fluid under pressure, substantially as described and shown and for the purpose set forth.

In testimony whereof I affix my signature in presence of two witnesses.

WILHELM WEBER.
